(57) **CLAIM**

The ornamental design for a sportman's vest, as shown and described.

DESCRIPTION

FIG. 1 is a front elevational view of the sportman's vest of the present invention;

FIG. 2 is a rear elevational view of the sportman's vest of FIG. 1;

FIG. 3 is a right side elevational view of the sportman's vest of FIG. 1;

FIG. 4 is a left side elevational view of the sportman's vest of FIG. 1;

FIG. 5 is a top plan view of the sportman's vest of FIG. 1; and,

FIG. 6 is a bottom plan view of the sportman's vest of FIG. 1.

The broken lines showing of camouflage in FIGS. 1,3 and 4 are for illustrative purposes only and form no part of the claimed design.
